UNITED STATES PATENT OFFICE.

ALBERT E. HOLADAY, OF NAUGATUCK, CONNECTICUT, ASSIGNOR TO THE AMERICAN WRINGER COMPANY, OF WOONSOCKET, RHODE ISLAND, A CORPORATION OF RHODE ISLAND.

PRESSURE-BAR FOR CLOTHES-WRINGERS.

1,289,460.

Specification of Letters Patent. Patented Dec. 31, 1918.

Application filed April 30, 1917. Serial No. 165,396.

To all whom it may concern:

Be it known that I, ALBERT E. HOLADAY, a citizen of the United States, residing at Naugatuck, in the county of New Haven 5 and State of Connecticut, have invented certain new and useful Improvements in Pressure-Bars for Clothes-Wringers, of which the following is a specification, reference being had therein to be accompanying drawing.

This invention relates to bearing plates for the pressure bar of a clothes wringer, and is especially adapted to be used in connection with a clothes wringer having an 15 automatic pressure release as disclosed in my application filed January 18, 1917, Serial No. 143,090, the object being to provide a bearing plate which is so constructed that the same can be placed in position on the 20 pressure bar without the use of fastening means such as screws and the like.

Another object of my invention is to provide a bearing plate which is provided with an attaching member in the form of a spike having spurs for holding the spike in position 25 within the pressure bar in such a manner that after the same has been once placed in position it will be securely held so as to support the bearing plate in position to be engaged by the pressure screw of the 30 wringer.

Another object of my invention is to provide a bearing plate which is preferably formed of a casting having at one end an attaching spike, and at the other end an 35 apertured boss to receive a releasing bar, said boss forming means for positioning the pressure spring.

Other and further objects and advantages 40 of the invention will be hereinafter set forth and the novel features thereof defined by the appended claims.

In the accompanying drawings,

Figure 1 is a detail section through a 45 portion of a clothes wringer having an automatic pressure release as disclosed in my application Serial No. 143,090 showing the application of my improved construction of bearing plate thereto;

Fig. 2 is a perspective view of the bearing plate detached;

Fig. 3 is a side elevation of a slightly modified form of bearing plate; and

Fig. 4 is a section taken on line 4-4 of Fig. 3.

55

Like numerals of reference refer to like parts in the several figures of the drawing.

In the drawing 1 indicates a movably mounted top bar of a clothes wringer which is provided with a pivoted latch 2 adapted 60 to engage a keeper 3 carried by the side bars 4 of a wringer frame, said latch being adapted to be engaged by a releasing bar 5. The movably mounted top bar 1 carries a pressure screw 6 adapted to coöperate 65 with the pressure bar 7 for adjusting the pressure on the pressure springs 8 of the wringer, the above description being given so that the application of my improved construction of bearing plate to a clothes 70 wringer can be readily understood.

My invention consists in providing a pressure bar 7 with a bearing plate at each end for the pressure screws 6 formed of a casting comprising a body portion 9 having a 75 groove 10 to receive the pressure screw 6, and an apertured boss 11 through which the releasing rod 5 passes over which is arranged the pressure spring 8 so as to hold the pressure spring in position to be adjusted by the pressure bar and to guide the releasing bar 5 in its vertical movement by the movement of the pressure roll which is clearly described in my application above referred to.

One end of the body portion 9 is provided with an obliquely extending spike 12 which is preferably formed with longitudinally disposed ribs 13 serrated to form spurs 14. In placing the bearing plate 9 in position upon the end of the pressure bar 7 a hole 15 is bored obliquely into the end of the pressure bar 7 and the spike 12 is forced into the bore thus formed, the spurs embedding themselves in the walls of the bore 90 so as to securely fasten the bearing plate 95 on the end of the pressure bar, with the end of the bearing plate in contact with the end of the pressure bar in such a manner that the bearing plate will be securely fastened to the pressure bar. The bore in the pressure bar 7 has a diameter slightly less than the diameter of the spike so that when the spike is forced into the bore, the longitudinally disposed ribs cut their own 100 passages so that the spurs embed themselves in

the wood of the pressure bar in such a manner that the bearing plate is attached rigidly to the pressure bar so that it will withstand the pressure exerted thereon by the pressure springs and pressure screws.

In the slightly modified form shown in Figs. 3 and 4 the body 9' is constructed substantially the same as shown in the preferred form, and is provided with a spike 12' extending obliquely therefrom from a point from the under side of the body so as to provide a vertically disposed shoulder 16' flush with the end of the body 17 in order to produce an abutting surface which strengthens the bearing and relieves the pressure bar from the pressure of the pressure screw so as to prevent the spike from splitting the pressure bar when in operation. By this construction it will be seen that the bore in the pressure bar 7' extends into the end thereof from a point spaced from the top of the pressure bar, while in the preferred form the spike of the pressure plate extends from the end of the plate.

From the foregoing description it will be seen that I have provided a bearing plate

for a clothes wringer which is provided with an attaching spike serrated for the purpose of embedding itself within the wood of the pressure bar for attaching the bearing plate securely to the pressure bar.

I claim:

1. As a new article of manufacture, a bearing plate for a pressure bar comprising a body portion having an integral serrated spike extending obliquely from one end thereof.

2. As a new article of manufacture, a bearing plate for a pressure bar, comprising a body portion having a groove to receive the pressure screw and provided with an apertured boss at one end, said body portion having an integral serrated spike extending obliquely from the opposite end thereof.

In testimony whereof I hereunto affix my signature in the presence of two witnesses.

ALBERT E. HOLADAY.

Witnesses:

F. THORNTON,
PATRICK O'CONNOR.
